UNITED STATES PATENT OFFICE.

WILLIAM RICHARD, OF BLOOMVILLE, OHIO, ASSIGNOR OF TWO-THIRDS TO
ADAM HOLLOWBACK AND DAVID ALLEN PARKS, OF SAME PLACE.

SHEARS.

SPECIFICATION forming part of Letters Patent No. 564,102, dated July 14, 1896.

Application filed March 2, 1896. Serial No. 581,507. (No model.)

To all whom it may concern:

Be it known that I, WILLIAM RICHARD, a citizen of the United States, and a resident of Bloomville, in the county of Seneca and State 5 of Ohio, have invented certain new and useful Improvements in Shears; and I do hereby declare that the following is a full, clear, and exact description of the invention, which will enable others skilled in the art to which it applies to make and use the same, reference 10 being had to the accompanying drawings, which form a part of this specification.

My invention relates to improvements in shears, principally designed for pruning trees, 15 plants, shrubs, and other similar objects, although it may be used for cutting purposes generally.

The object of the invention is to provide an improved construction of the same, which 20 shall possess superior advantages with respect to efficiency in use.

The invention consists in the novel construction and combination of parts hereinafter fully described and claimed.

25 In the accompanying drawings, Figure 1 is a side elevation of a pair of shears constructed in accordance with my invention. Fig. 2 is a view of one of the blades and handles detached, looking from the inner side. Fig. 3 30 is a similar view of the other blade and handle. Fig. 4 is a cross-section on the line xx , Fig. 1.

In the said drawings, the reference-numeral 1 designates a handle, preferably of steel, 35 formed at its outer end with a curved jaw 2, provided with a cutting edge 3. It is also provided upon one side with a curved metal strip 4, riveted or screwed thereto, and confined between this strip and the jaw is a strip 40 5, of leather or other similar material, to prevent dulling the blade of the other section of the shears, hereinafter described. The handle near its juncture with the jaw is formed with two holes 6, and in rear thereof with a 45 stud or stop 7. The blade is also provided with a hand or finger stay 8.

The numeral 9 designates the other handle or section formed with a curved cutting-blade 10, and formed with an oblong hole 12 and, 50 with a cam 13. Passing through the holes 6 in handle 1, and through the oblong hole 12,

is a screw-bolt 14, to which is connected a link 15. Through the other end of said link passes a screw-bolt 15^a, which also passes through the other hole 6, on which is journaled a roller 16. A spring 17 is provided between the two handles for spreading apart the jaw and blade.

In using the device the handles are pressed toward each other, when the cam 13, acting 60 against the roller 16, will serve as a fulcrum for the handles, and the blades will approach the cutting edge of the jaw to make a shear cut.

It will be seen that no strain comes upon 65 the bolt 14, which works in the oblong slot, and simply forms a support for the link, the strain or pressure all coming upon the cam and roller, and as the latter rotates during the operation, the friction is considerably reduced. While the bolt 14 simply acts as a support for the link, it securely holds the blade to the link and helps support the latter and keep it in position. The blade is also held in a true plane by means of the bolt and 75 link, and prevented from twisting.

There are other advantages possessed by my invention which are obvious and need not be enumerated here.

The cutting-blade and jaw may be constructed as shown, with two short handles operated by hand, or the jaw may be secured to a long handle and the blade provided with an operating wire or rod, when high objects, such as trees, are to be trimmed, as in the 85 ordinary tree-trimmers.

Having thus fully described my invention, what I claim is—

1. As an improved article, a pair of shears comprising a handle provided with two bolt-holes and formed with a curved jaw having a cutting edge, and another handle having a curved cutting-blade, a cam and an oblong hole, the link, the screw-bolt passing through said oblong hole, the link and the other handle, the screw-bolt passing through the other end of the link into the other handle, and the roller journaled thereon with which said cam engages, substantially as described.

2. The combination with the handle formed with two bolt-holes, a jaw with a cutting edge, and the curved leather strips secured to said

jaw, of the handle formed with a curved blade, a cam, and an oblong hole, the link, the bolt passing through said link, oblong hole and the other handle, the bolt passing through the 5 other end of the link into the other handle, and the roller journaled thereon with which said cam engages, substantially as described.

In testimony that I claim the foregoing as my own I have hereunto affixed my signature in presence of two witnesses.

WILLIAM RICHARD.
